UNITED STATES PATENT OFFICE.

ALFRED A. DENNIS, OF GRAND RAPIDS, MICHIGAN.

VEHICLE-SIGNAL.

1,364,485.

Specification of Letters Patent. Patented Jan. 4, 1921.

Application filed April 8, 1919. Serial No. 288,619.

To all whom it may concern:

Be it known that I, ALFRED A. DENNIS, a citizen of the United States, residing at Grand Rapids, county of Kent, State of Michigan, have invented certain new and useful Improvements in Vehicle-Signals, of which the following is a specification.

This invention relates to improvements in vehicle signals.

10 The main objects of this invention are:

First, to provide an improved signal for motor vehicles which is easily installed upon a vehicle either as an attachment or embodied in a structure during manufacture.

15 Second, to provide an improved motor vehicle signal which is very easy to operate and also positive in its operation.

Further objects, and objects relating to structural details, will definitely appear 20 from the detailed description to follow.

I accomplish the objects of my invention by the devices and means described in the following specification. The invention is clearly defined and pointed out in the claims.

25 A structure which is a preferred embodiment of my invention is clearly illustrated in the accompanying drawing, forming a part of this specification, in which:

Figure I is a side view of a motor vehicle 30 having my improvements embodied therein, parts of the vehicle body being broken away to show structural details, the parts being mainly shown conventionally.

Fig. II is an outer side elevation of the 35 rear signal of the embodiment of Fig. I, the rear fender being shown in section.

Fig. III is a front view or view looking from the left of Fig. II, with a portion of the housing removed, one of the signal arms 40 being shown in its actuated position by dotted lines.

Fig. IV is a detail view on a line corresponding to line 4—4 of Figs. I and V, showing the arrangement of the control valves.

Fig. V is a detail section on a line corresponding to line 5—5 of Fig. IV.

Fig. VI is a detail view of the parts shown in Fig. II looking from the left with front signal member and its housing or support removed.

Fig. VII is a cross section through one of the actuating plungers and its cylinder.

In the drawing similar reference characters refer to similar parts throughout the

several views, and the sectional views are taken looking in the direction of the little arrows at the ends of the section lines.

Referring to the drawing, 1 represents the body of a motor vehicle, 2 an internal combustion motor, and 3 the manifold thereof. These parts are shown conventionally and are illustrated to show the application or adaptation of my improvements.

The signal members may be mounted on any part of the vehicle desired. In the structure illustrated I have shown them mounted on the front and rear left side fenders, there being a pair of signal members 4 and 5 at the rear mounted in a housing or support 6. The signal member 4 is pivoted at 7 while the signal member 5 is pivoted at 8 within the housing, there being a partition 9 dividing the housing into compartments for the signal members. Each signal member is provided with an actuating plunger 10, the cylinders 11 and 12 of which are connected by the pipes 13 and 14 to the valve casing 15. This valve casing is in turn connected to the manifold by the pipe 16. The pipes or conduits 13 and 14 are controlled by the valves 17 and 18 respectively, the manifold conduit 16 being connected to the valve casing between these valves 17 and 18 as shown in Figs. IV and V.

The valve 17 is provided with an operating rod 19 mounted on the steering post 20 so as to be operated by the knee of the driver, the rod having a crank-like offset 21 therein,—see Fig. I.

The valve 18 is connected by the link 22 to the brake rod 23 or some other portion of the brake mechanism so that when the brake is actuated to stop the vehicle the cylinder 12 is connected to the manifold and suction 95 actuates the arm or signal member 5 which has the word "Stop" thereon.

When the valve 17 is opened the direction signal 4 is actuated, its actuating cylinder 11 being then connected to the manifold 100 so that the suction draws down the plunger.

A single signal member 25 is mounted on the front left fender, it being provided with a cylinder and plunger, the same as described, connected by the pipe 26 to the pipe 13, so that both the front and rear signal members are actuated when the valve 17 is opened.

The plungers are connected to the signal members by means of the flexible cables 27

arranged over eccentrics 28 on the signal member pivots.

To prevent water and dust working into the cylinders the plungers have housing sleeves 29 secured thereto to embrace the upper ends of the cylinders.

To attract attention to the signal mechanism I preferably provide the rear housing with a lamp 30 which may serve as a tail lamp for the vehicle, the housing being provided with a lens 31 opposite the lamp.

The signal members have a series of holes 32 alined with the lamp when the signal members are in their normal position. The signal members may be otherwise formed to permit the passage of the light.

To further attract attention to the signal I preferably mount a small lamp 33 at the outer end of the signal member, the same being connected by the wires 34 to the wiring for the lamp 30, so that they may be continuously lighted.

My improved signal device may be readily installed as an attachment or built into a motor vehicle in the manufacture thereof. I have illustrated and described the same mainly in conventional form as structural details may be greatly varied, also the adaptation thereof to the vehicle.

I have not attempted to illustrate or describe various modifications and adaptations as I believe the disclosure made will enable those skilled in the art to which my invention relates to embody or adapt the same as may be desired.

Having thus described my invention, what

I claim as new and desire to secure by Letters Patent, is:

1. In a motor vehicle including a body, an internal combustion motor and an intake manifold therefor, the combination of a pivotally mounted signal member carried by said body, an eccentric on the pivot of said signal member, an actuating plunger for said signal member, a flexible connection for said eccentric to said plunger, a cylinder for said plunger, a housing sleeve slidably embracing said cylinder and secured to the plunger, said housing sleeve constituting a guide for the plunger and a shield for the cylinder, a conduit connecting said cylinder to said manifold, and a control valve for said conduit whereby when the valve is opened the signal member is actuated by suction.

2. The combination with an internal combustion engine, of an intake pipe therefor, a movable signal member, a signal actuating plunger connected to said signal member, a cylinder therefor connected to said intake pipe, and a housing sleeve slidably embracing the upper end of the cylinder and secured to the plunger, for the purpose specified.

In witness whereof I have hereunto set my hand and seal in the presence of two witnesses.

ALFRED A. DENNIS. [L.S.]
